FRANCIS E. ASHTON, OF CHESTER, PENNSYLVANIA, ASSIGNOR TO ABERFOYLE MANUFACTURING COMPANY, OF CHESTER, PENNSYLVANIA, A CORPORATION OF PENNSYLVANIA

SHUTTLE

Application filed December 5, 1928. Serial No. 323,819.

This invention relates to a shuttle or weft carrying device for looms and particularly to a loom of the type shown and described in my application for "loom", executed and filed on even date herewith, Serial No. 5 323,818.

This shuttle is akin to another application 10 for "shuttle", executed and filed by me on even date herewith, Serial No. 323,817, and also intended for use with the loom above 15 mentioned.

The object of the invention herein is to provide a shuttle that will receive a loop of 20 weft thread and after it has been passed through the warp shed and returned to its initial position, will be operated to sever the loop held by it and to receive a new loop for a successive operation.

Another object of the invention is to provide 25 means to be automatically operated by the loom to perform the above function.

According to the invention, the shuttle is conventionally shaped and provided with a rotatable member having a plurality of 30 hooks for successively severing the loop of woven weft and receiving a new loop of weft thread to be woven, and ratchet means adapted to be operated by the loom for rotating the said hook member at the precise 35 moment when one loop is to be disengaged, and a new loop received by the hook member.

The invention also contemplates the employment of step-up gears for providing a 40 higher speed of rotation for the hook member than for the ratchet means.

The drawing illustrates an embodiment of the invention and the views therein are as follows:

- 40 Figure 1 is a side view of the shuttle,
- Figure 2 is a top plan view thereof,
- Figure 3 is a longitudinal sectional view taken on the line 3—3 of Figure 2 and looking in the direction of the arrows,
- 45 Figure 4 is a cross-sectional view on the line 4—4 of Figure 2,
- Figure 5 is a similar view on the line 5—5 of Figure 4, and
- 50 Figure 6 is a like view on the line 6—6 of Figure 2.

In configuration the shuttle is substantially the same as the conventional shuttle and comprises a body 11 having the usual pointed steel ends 12 with the fibre plate 13 therebetween. The body 11 is usually constructed 55 of wood or some very light material and is recessed as shown at 14 in Figure 3. This recess is provided with a metallic bearing member 16 which is flush with the top of the shuttle and such bearing member has a cut-out portion or recess 17 therein in horizontal alignment with the recess 18 extending transversely through the body 11 of the shuttle and shown in Figures 1 and 4 so that there is formed a transverse channel extending 60 entirely through said shuttle.

The bearing member has an overhanging lip 19 which fits against the outer vertical wall of the recess 14 and has a plate part 21 65 whose outer end fits against the inner vertical wall of the recess 14.

The space immediately below the overhanging lip 19 is occupied by a plate 22 which has a knife edge 23 on the left hand side of the same and by a rotatable hook member 24 70 mounted on a shaft 26 which extends into a recess 27 in said bearing and is provided in said recess with a pinion 28 which meshes with another pinion 29 in said recess and secured to a shaft 31 which extends longitudinally and is provided on that part which 75 extends in the recess 32 above the plate 21 with a ratchet wheel 33.

As illustrated in Figure 5, the pinions 28 and 29 are of different diameters and their 80 ratio is 2 to 1 so that a single rotation of the shaft 31 will rotate the shaft 26 and the rotatable hook member 24 twice.

The side of the body member 11 is grooved, 85 as shown at 34 in Figures 1 and 2, while that portion of the body lying beyond the recess 18 and toward the end of the shuttle is cut back a considerable distance, as shown at 36 in Figures 1 and 2. This is for the purpose 90 of allowing weft thread to be drawn into the recesses 17 and 18 where it can be engaged by one of the hooks 37 on the hook member 24.

Extending transversely across the channel formed by the recesses 17 and 18 is a 95 groove 38 so positioned that the tip of each 100

of the hooks 37 will extend into same when at their lowermost position.

It will be noted that the hooks 37 all extend in the same general direction when passing any given point and when a thread has been engaged by the lowermost hook 37 and been woven into the fabric, and the shuttle returned to its original position, mechanism on the loom will automatically rotate the ratchet wheel 33 so as to draw the thread over the edge of the knife 23, thus severing it and at the same time the succeeding hook will receive a new loop of thread to be woven into the fabric.

15 A more comprehensive and better understanding of the mechanism of the loom mentioned in the foregoing pending application will tend to clarify the operation of the mechanism herein.

20 The pinions 28 and 29 have been provided because in a direct connection, the action of a pawl upon the ratchet wheel would hardly be great enough to provide a quarter revolution or a 90° movement of the hook member.

25 It will, however, be readily seen that when the hook member is rotated 90° with the thread lying in the lowermost hook 37, that thread will be engaged with the knife 23 and severed, while a new thread which is placed across the groove 38 will be picked up and held by the succeeding hook.

The shuttle illustrated may be changed in various ways without departing from the invention herein set forth and hereafter claimed.

I claim:—

1. A shuttle comprising a body and rotary means mounted therein for intermittently receiving and holding a loop of weft thread.

40 2. A shuttle comprising a body and a rotatable hook member for receiving and holding a loop of weft thread.

3. A shuttle comprising a body, rotary means for receiving and holding a loop of weft thread, and means for rotating said first means.

45 4. A shuttle comprising a body, a rotatable hook member for receiving and holding loop of weft thread, and means for rotating said hook member.

5. A shuttle comprising a body, rotary means for receiving and holding a loop of weft thread, and means for severing said loop when said rotary means is rotated.

55 6. A shuttle comprising a body, rotary means for receiving and holding a loop of weft thread, and a knife for severing said loop when said rotary means is rotated.

7. A shuttle comprising a body, rotary means provided with a plurality of hooks for receiving and holding a loop of weft thread, and means for severing said loop when said rotary means is rotated.

60 8. A shuttle comprising a body, rotary means provided with a plurality of hooks for

receiving and holding a loop of weft thread, and a knife for severing said loop when said rotary means is rotated.

9. A shuttle comprising a body, rotary means for receiving and holding a loop of weft thread, and a ratchet wheel for rotating said means. 70

10. A shuttle comprising a body, rotary means provided with a plurality of hooks for receiving and holding a loop of weft thread, 75 and a ratchet wheel for rotating said means.

11. A shuttle comprising a body, rotary means for receiving and holding a loop of weft thread, a ratchet wheel for rotating said means, and means for severing said loop when 80 said rotary means is rotated.

12. A shuttle comprising a body, rotary means for receiving and holding a loop of weft thread, a ratchet wheel for rotating said means, and a knife for severing said loop 85 when said rotary means is rotated.

13. A shuttle comprising a body, rotary means for receiving and holding a loop of weft thread, a ratchet wheel for rotating said means, and means for stepping up the speed 90 of rotation of said rotary means.

14. A shuttle comprising a body, rotary means provided with a plurality of hooks for receiving and holding a loop of weft thread, a ratchet wheel for rotating said means, and means for stepping up the speed of rotation of said rotary means. 95

15. A shuttle comprising a body, rotary means for receiving and holding a loop of weft thread, a ratchet wheel for rotating said means, and step-up gears between said ratchet wheel and rotary means. 100

16. A shuttle comprising a body, rotary means provided with a plurality of hooks for receiving and holding a loop of weft thread, 105 a ratchet wheel for rotating said means, and step-up gears between said ratchet wheel and rotary means.

17. A shuttle comprising a body, a pair of shafts, rotary means on one shaft for receiving and holding a loop of weft thread, 110 means on the other shaft for rotating same, and gears between said shafts.

18. A shuttle comprising a body, a pair of shafts, rotary means provided with a plurality of hooks on one shaft for receiving and holding a loop of weft thread, a ratchet wheel on the other shaft for rotating same, and gears between said shafts. 115

19. A shuttle comprising a body, a pair of shafts, rotary means on one shaft for receiving and holding a loop of weft thread, means on the other shaft for rotating same, gears between said shafts, and means for severing said loop when said rotary means is rotated. 120

20. A shuttle comprising a body, a pair of shafts, rotary means provided with a plurality of hooks on one shaft for receiving and holding a loop of weft thread, a ratchet wheel on the other shaft for rotating same, gears 125 between said shafts, and means for severing said loop when said rotary means is rotated.

between said shafts, and means for severing said loop when said rotary means is rotated.

5 21. A shuttle comprising a body and rotary means for receiving, holding and discharging by severance a loop of weft thread.

22. A shuttle comprising a body and rotary means mounted therein for receiving, holding and discharging by severance a loop of weft thread.

10 In testimony whereof I have signed my name to this specification.

FRANCIS E. ASHTON.
